UNITED STATES PATENT OFFICE.

JOHN T. PSARSKI, OF CLEVELAND, OHIO.

CENTRIFUGAL DRIER.

1,071,956.

Specification of Letters Patent. Patented Sept. 2, 1913.

Application filed July 27, 1910. Serial No. 574,075.

To all whom it may concern:

Be it known that I, JOHN T. PSARSKI, a subject of the Czar of Russia, residing at Cleveland, in the county of Cuyahoga and State of Ohio, have invented certain new and useful Improvements in Centrifugal Driers, of which the following is a specification.

In utilizing dyeing machines generally and in some particular instances, the vat or cylindrical kettle is provided with a distributing member comprising a false bottom and a central distributor projecting upward from the center of the false bottom and both of these parts are provided with discharge openings. The distributing member in the tank forms the mass of material to be dyed in an annulus and if the cover placed on the dyeing machine is provided 20 with perforations near the periphery only, then the circulation of the dye liquor is such that the mass of wool, cotton, or other material dyed is forced outward and upward toward the upper outer corner around 25 the machine, and the material nearest this point tightly compacted and more so than the material toward the bottom and center, so that the greatest density is at this point and rendering greater resistance to the circulation of air through the mass at such 30 point. The present machine, therefore, is designed for use in conjunction with dyeing machines generally but in more particularly for use in conjunction with the type of machine just set forth.

This invention, therefore, relates to improvements in devices termed "whizzers", which are otherwise known as centrifugal driers.

More specifically the invention contemplates the employment of a suitable base having mounted thereon, in suitable swinging supports, a casing in which is supported a suitable motor having a vertically disposed shaft on the upper end of which is a basket having a solid bottom with a cylindrical side wall provided with main discharge perforations near its upper edge and smaller perforations throughout the remainder of the side. This basket is adapted to receive a false bottom, a central distributing member of a dyeing machine such as is set forth in my prior Patent No. 955,993 and in my prior application Ser. No. 546,414, filed February 28, 1910, and consists of a false bottom and a substantially cylindrical cen-

tral distributing member provided with a shank having an eye receiving a load hook for a suitable hoist. Upon the basket is a cover having discharge openings near its periphery and an upwardly extending connection for receiving a hot air pipe leading from a suitable air heater not shown. This pipe passes into a suitable stuffing box in the connection. A further cover is provided upon the device and it consists of two halves bolted together and secured to the periphery of the machine by suitable bolts. A suction pipe leads from a pump to the casing and serves as a means for exhausting the air therefrom. It is also part of the invention to provide the basket with blades around its periphery and upon its cover for causing the air to be thrown from the center of the device out through the perforated sides and into the casing from which it is discharged through the exhaust pipe.

More specifically the invention relates to certain details of construction hereinafter set forth in the following description, drawings and claims.

Referring to the drawings, Figure 1 is a sectional view of a machine constructed according to my invention; Fig. 2 is a top plan view showing the two parts of the cover; Fig. 3 is a vertical section of a machine having fan blades around the periphery of the basket and upon the cover; Fig. 4 is a top plan view of the cover with part in section; and Fig. 5 is a detail view of a portion of the side wall of the basket showing the large and small perforations.

In carrying out the invention any preferred form and construction of parts may be employed so long as they possess the necessary characteristics, but I have shown one embodiment in the drawings which is highly effective in operation, and in such embodiment, 1 is a suitable base secured to the masonry or other foundation, and it is provided with upwardly projecting supports 2 each provided with a ball socket 3. Preferably there are three of these supports spaced equal distances apart around the machine, but only one is shown in the drawings. The socket 3 receives a ball 4 on the end of a bolt 5 passing through an opening in a flange 6 of the main whizzer casing 7. This casing is provided with a central opening 9 and with a flange 10 about such opening and receiving upon it a suitable motor casing 11. This motor may be of any suitable type, and

since its construction and arrangement constitute no part of my invention, no further description will be given. The motor, however, is provided with a shaft 12 projecting out of the casing 11 and extending well up into the main casing 7. Upon this shaft, which is tapered as shown, is mounted a basket 13 having a side wall 14 with small openings 14' therein through which water and some air passes, but the main discharge is through main discharge openings 15 adjacent to the upper edge of the side wall. The arrangement of the bottom of the basket is such that the false bottom 16 and central distributing member 17 of a dyeing machine, not shown, may be inserted therein with the mass 18 of material thereon. The side wall of the basket receives a suitable cover 19 having a flange 20 extending down on the outside and provided with perforations 20' adapted to register with the main discharge openings 15. The cover itself is provided adjacent its edge with discharge perforations 19' and at the center with an upwardly extending dome-shaped portion 21 provided with a connection 22 and receiving a pipe 23. A suitable stuffing box 24 is arranged about this pipe to prevent leakage of air. The pipe 23 leads to a suitable air heater of any design or construction, and not shown in the drawings. The main casing 7 is provided with suitable ears 25 which receive bolts 26 upon which nuts 27 are provided for holding the cover members 28 and 29 in place. These cover members are secured together by bolts 30 passing through ears 31. These two half cover members fit tightly about the pipe and about the stuffing box and connection between the dome-shaped member 21 and the air pipe. The suction pipe 32 leads into the bottom of the casing and it is connected with any suitable pump 32' for exhausting the air pressure in the casing.

The material operated upon by the machine is in the form of an annulus tightly compacted toward the upper outer corner as a result of the dyeing operation in the dyeing machine, and on this account it is necessary to increase the discharge at this point, so as to permit as free a passage of air as possible at the upper outer corner where the material is densest. Upon the rotation of the basket and upon supplying hot air to the interior thereof and upon further causing the air to be drawn from the outer casing, the material is thrown against the side and against the top, and the rush of air through the discharge openings causes the material to seek the upper outer corner when the draft will be almost entirely through the mass of material when all moisture will be dried from the mass and it will be ready for other work. The smaller perforations below the main discharge open-

ings in the side wall serve to vent a smaller amount of the water and some of the air but the material at this point is not very dense and needs very little vent to permit a proper circulation of the air through it.

In the modification shown in Figs. 3 and 4, the basket 13 is provided upon its periphery with blades 33 which are turned slightly to the rear, as shown in Fig. 4, and they are adapted to assist the circulation of the air through the discharge perforations in the side wall. The cover may also be provided with fan blades 33' which assist the circulation of the air through the perforations in the cover.

Having described my invention, I claim:

1. In a drier, a receptacle for the material having an air discharge and an air inlet, means for rotating such receptacle to cause the material to be compacted against the discharge, means for supplying a drying medium to the interior of the mass of material, an outer casing enveloping the receptacle, and means for creating a partial vacuum within the outer casing.

2. In a centrifugal drier, a casing, a motor, a basket for the material and comprising top and bottom members and an intervening side wall having main discharge openings adjacent the junction of the side wall and one of said top and bottom members only, and means for supplying hot air to the material at a point opposed to the discharge.

3. In a centrifugal drier, a casing, a motor, a basket for the material and comprising an imperforate bottom member driven by the motor, a side wall having main discharge openings adjacent its upper edge, and a cover having discharge openings adjacent its periphery only, and means for supplying hot air to the interior of the basket.

4. In a centrifugal drier, a casing, a motor, a basket for the material to be dried comprising an imperforate bottom member driven by the motor, a side wall having main discharge openings adjacent its upper edge, a cover having discharge openings adjacent its periphery only, a dome at the center of said cover, a hot air delivery pipe entering said dome, a cover for said casing, and means for exhausting the air from said casing.

5. In a centrifugal drier, a casing, a motor carried by said casing and having a vertically disposed driving shaft, a basket mounted upon said shaft and comprising an imperforate bottom and a perforated side wall, a cover for said basket having a centrally located dome provided with a connection including a stuffing box, a hot-air pipe entering said connection and passing through said stuffing box, a two-piece cover for said casing, means for securing the cover upon the casing, means for securing

the parts of the cover together, and means for exhausting the air from said casing.

6. In a centrifugal drier, a cylindrical casing, a motor mounted on the bottom of said casing, a basket driven by said motor and comprising a bottom and a perforated side wall, blades carried by said wall, a cover for said basket having a central opening, a hot air pipe entering said opening, a stuffing box carried by the cover and arranged about said hot-air pipe, a two-piece cover for said casing having an opening therein for receiving the stuffing box and for receiving the hot-air pipe, and means for exhausting the air from the lower part of said casing.

7. In a centrifugal drier, a casing, a motor, a basket for the material and comprising top and bottom members and an intervening side wall and having main discharge openings adjacent the junction of the side wall and one of said top and bottom mem-

bers only, means for supplying hot air to the material at a point opposed to the discharge, and suitable blades upon the outside 25 of the side wall and upon the cover.

8. In a centrifugal drier, a casing, a motor, a basket for the material and comprising top and bottom members, one of which is provided with discharge perforations adjacent its periphery only, and a side wall having discharge perforations adjacent the other member having discharge perforations, means for supplying hot air to the material at a point opposed to the discharge, 30 and suitable blades upon the outside of the side wall and upon the cover.

In testimony whereof I affix my signature in presence of two witnesses.

JOHN T. PSARSKI.
